Primary Examiner — Michael A. Pratt*(74) Attorney, Agent, or Firm* — Armstrong Teasdale LLP(57) **CLAIM**

We claim the ornamental design for a lid adapter for wet/dry vacuum cleaner with detachable blower, as shown and described.

DESCRIPTION

FIG. 1 is a front perspective view of a lid adapter for wet/dry vacuum cleaner with detachable blower showing the new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The ornamental design which is claimed is shown in solid lines in the drawings. Broken lines, if present in the drawings, are for illustrative purposes only and form no part of the claimed design.
